UNITED STATES PATENT OFFICE.

ERICH E. MUELLER, OF ST. LOUIS, MISSOURI.

CYLINDER-COCK FOR STEAM-ENGINES.

SPECIFICATION forming part of Letters Patent No. 268,815, dated December 12, 1882.

Application filed October 13, 1882. (No model.)

To all whom it may concern:

Be it known that I, ERICH EDWARD MUELLER, a citizen of the United States, residing at St. Louis, in the county of St. Louis and State of Missouri, have invented certain new and useful Improvements in Cylinder-Cocks for Steam-Engines; and I do declare the following to be a clear, full, and exact description of the invention, such as will enable others skilled in the art to which it appertains to make and use the same, reference being had to the accompanying drawings, and to the letters and figures of reference marked thereon, which form a part of this specification.

My invention relates to the class of cylinder attachments in which cocks are employed for relieving the cylinder of the water of condensation, and which are automatically opened and closed by moving parts of the engine.

It consists in a three-way cock connected to the cylinder by suitable pipes and adjustable mechanism for operating the same for relieving the cylinder of the water of condensation, all of which will be more particularly described in the specification and pointed out in the claims.

Figure 1 is a side view of an engine with my device attached. Fig. 2 is a view of end of the rod that connects the valve-lever with the pendent arm. Figs. 3, 4, and 5 are sectional views of the cock, showing the different positions of the same.

To cylinder B, near each end, I attach one end of the pipes M M, the other ends terminating in either side of the body of the cock L. The cock is of the ordinary plug kind, part being cut away on one side to permit of a discharge when registering with two of the ports. The body of the cock has three ports, one leading to each end of the cylinder, and a third being a discharge common to both of the cylinder communicating pipes. The cock L has a slotted lever, I. In this slot is an adjustable wrist-pin, J, to which is attached the rod H, the other end of the rod having a hook, h. To the cross-head A of the valve-rod D is attached, by a bolt or otherwise, the pendent arm E. This arm may be attached to any part of the engine where sufficient motion can be

had to oscillate the valve. In the lower part 50 of the arm E is a slot, F, having an adjustable wrist-pin, G, similar to the one on the valve-lever, and to which the detachable hook end of the rod H is attached, said end being fully shown in Fig. 2. The object of the slots in 55 the arm and lever and the adjustable wrist-pin is to so adjust the valve that its openings will just permit the water of condensation to escape and prevent waste of steam.

The operation is as follows: Before starting 60 the engine the rod H is disconnected from the arm E by lifting it up with the hand. The steam-valve is slightly opened to permit steam to enter the cylinder to heat the same at the same time by means of the rod H. The cock is 65 opened alternately to each end of the cylinder, thereby letting out any water. Having heated the cylinder, the hook h of the rod H is connected to the arm E by the wrist-pin G, and the engine is started.

It will be readily seen from the foregoing 70 description that motion will be imparted to the cock in proportion to the adjustment of the rod with the lever and arm, and that the water of condensation will be discharged 75 automatically at each stroke of the piston.

Having fully described my invention, what I claim as new, and desire to secure by Letters Patent, is—

1. The combination, in a steam-engine having a single cock to relieve either end of the cylinder of water, of the lever I, rod H, adjustable pin G, slotted arm E, and the valve-rod D, substantially as shown and described.

2. In a steam-engine having a single cock 85 to relieve either end of the cylinder of water, the combination therewith of the slotted lever I, adjustable wrist-pin J, rod H, having the hook h, adjustable pin G, slotted arm E, valve-rod, and cross-head A, substantially as shown 90 and described.

In testimony whereof I affix my signature in presence of two witnesses.

ERICH EDWARD MUELLER.

Witnesses:

ISRAEL E. RUSSELL,
ALFRED AVERY.
